[57] CLAIM

The ornamental design for a wire clip fencing tool, as shown and described.

DESCRIPTION

FIG. 1 is a front elevational view of my wire clip fencing tool showing my new design;

FIG. 2 is a right side perspective view of FIG. 1, the left side perspective view being a mirror image;

FIG. 3 is a fragmented left side perspective view of FIG. 1, shown with the bottom left side cut away for clarification of FIG. 6;

FIG. 4 is a rear elevational view of FIG. 1;

FIG. 5 is a top plan view, right side, of FIG. 1; and,

FIG. 6 is a bottom plan view, left side, of FIG. 1.
